UNITED STATES PATENT OFFICE.

EMILE DESMOULINS, OF PARIS, FRANCE

APPARATUS OPERATED BY MULTICYLINDER INTERNAL-COMBUSTION ENGINES.

Application filed June 8, 1920. Serial No. 387,401.

To all whom it may concern:

Be it known that I, EMILE DESMOULINS, a citizen of the French Republic, residing at Paris, France, have invented certain new and useful Improvements in or Relating to Apparatus Operated by Multicylinder Internal-Combustion Engines, as set forth in the following specification.

This invention relates to apparatus fitted 10 with internal combustion engines, in the case of which it is required to work at times with full power and at other times with greatly reduced power. Its most useful application is to powerful automobile vehicles, but it may be adapted, where found desirable, to other apparatus or mechanisms operated by internal combustion engines.

The invention has for its primary object to enable the engines to be utilized in 20 a more economical manner than has hitherto been the case.

According to the general principle of the invention I fit the automobile or other apparatus with two internal combustion engines 25 turning in the same direction and having a number of cylinders, and the essential feature of the invention consists in so arranging the associated parts of said motors that their torques can be fully utilized in simultaneous operation.

In the preferred construction the cylinder or cylinders which can be brought individually or independently into operation are grouped separately from the others.

The invention also includes certain constructional embodiments of its principles and certain arrangements such as differential gears fitted to the unequal torques of the motors which are preferably used in 40 combination, and which will be more fully described hereafter.

In order that the invention may be clearly understood, I will now proceed to describe the same with reference to the accompanying drawing, which however is given merely by way of example.

Fig. 1 of the drawing shows to a small scale, and in an absolutely diagrammatic manner and in plan the principal parts of 50 a powerful automobile vehicle constructed according to the invention, or transformed thereto, by replacing its ordinary motor, by two motors functioning according to the main principle of the invention.

Fig. 2 shows to a larger scale, and in a less diagrammatic manner and in longitudi-

dinal vertical section, a motor constructed and arranged, and combined with a change speed mechanism, according to the invention. The latter figure is also intended to show the application of the invention in the construction of an automobile vehicle of high power.

Supposing I desire to construct an automobile vehicle of 24 horse power. I proceed 60 in the embodiment illustrated in the drawing substantially in the following manner:

I provide for the driving motor, two internal combustion engines A¹ and A².

The maximum power of these engines is equal to the maximum which it is required to employ, consequently 24 horse power in the case under consideration, in the aggregate.

The feeble motor A¹ of the two motors has a maximum power equal to that which is required to drive the vehicle at the lowest rate, for instance that allowed in large towns, say 8 horse power.

The motor system may, with advantage comprise six cylinders divided into two groups, the feeble group A¹ having two cylinders and the stronger group A² having four cylinders. The supply and valve systems of these two groups, which are not shown, are distinct from one another.

The cylinders may be arranged in the known manner shown in Fig. 1, so that the respective crank shafts a¹ and a² are parallel and not co-axial; or preferably, and as shown at Fig. 2, they may be so arranged according to the invention that their respective crank shafts a¹ and a² are in alignment.

I further provide mechanism interposed between the two sets of cylinders and the wheels controlled therefrom such that it permits the wheels to be driven, as required, from one or other of the two sets of cylinders, or from both sets simultaneously.

This mechanism, may with advantage, in the case where the cylinders and crankshafts have been arranged in alignment, comprise a single shaft c, located parallel to the said 105 crank shafts so that it may be operated from pinions carried by axially fixed portions (keyed on the single shaft to be driven) of clutches. The axially movable portions of said clutches are loose on the said driven shaft, and carry gear wheels which mesh with pinions carried by the crankshafts,

means being added to simultaneously or individually throw in or out of operation the said clutches as required, and other usual and appropriate constructional details being 5 added. This construction may be considered as a simplified form of the construction shown in Fig. 1.

Although an excellent result may be obtained by adopting the construction just described, I prefer to combine with the arrangements in question change speed mechanism which permits a perfect balance between the unequal torques of the feeble and strong motors and which may be of the type 15 disclosed in U. S. Patent No. 1,407,643 of February 21, 1922, granted to me.

This mechanism is preferably combined with the motor of the automobile vehicle in the manner indicated in Fig. 2.

20 In this figure the pinions b^1 and b^2 are operated from corresponding pinions e^1 and e^2 of different diameters keyed to the crank shafts a^1 a^2 .

d^1 d^{10} and d^2 d^{20} are the clutches, which 25 in this case are carried on the shaft c .

f is a pinion or sun wheel mounted loosely on an extension of the shaft c and connected to a long sleeve f^1 extending to the movable portion d^{10} of the clutch d^1 , d^{10} which is 30 carried by the said extension, so that when the movable portion is in the operative position, the sun wheel f moves with the fixed portion d^1 of the said clutch.

35 g are corresponding satellites, the axles of which are carried, at one end by a flange or enlargement provided for the purpose upon a planet sleeve h surrounding the last mentioned sun wheel sleeve, and at the other extremity connected to a ring i forming the 40 axially immovable, loose part of a double clutch. The satellites g mesh with the sun wheel f .

45 i^0 is another sleeve slidable, on a long key on the extension of the shaft c and forming or carrying the axially movable middle portion of the double clutch to which the axially fixed clutch portion i belongs. Its axial position is determined by that of the planet sleeve h , which itself is axially fixed by 50 appropriate means not shown.

55 j is an internally toothed annulus, so constructed and arranged as to mesh with the satellites g , and integral with an annulus sleeve j^2 surrounding the sun wheel and planet sleeves previously referred to and carrying the movable portion d^{20} of the clutch d^2 , d^{20} which surrounds the said annulus sleeve j^2 . The construction is such that when the said movable portion d^{20} is 60 in the operative position, the annulus j is connected to or moves with the fixed portion d^2 of the said clutch.

65 k^0 is a piece of the double clutch i k , connected slidably by means of a key with the annulus j , so constructed and arranged with

respect to the outer surface of the middle piece k of said clutch, the piece i^0 , that it forms the outer portion of the double clutch i k k^0 of which it constitutes the moving portion. 70

l and m are brake pulleys, keyed respectively upon the shaft c and the planet sleeve h .

n is another supplementary brake pulley formed on the part carrying the annulus j . 75

o^1 and o^2 are springs interposed respectively between the moving portion d^{10} of the clutch d^1 , d^{10} , and a fixed part, and between the moving part d^{20} of the clutch d^2 , d^{20} and another fixed part, so that the said springs 80 tend to maintain these movable parts in the operative positions.

p is a spring interposed between a fixed portion and the movable member i^0 of the clutch i , i^0 , so that it tends to keep this portion in the operative position. 85

q is another spring considerably weaker than that last mentioned interposed between projections or the like formed for the purpose upon the movable portions i^0 and k^0 90 of the clutches i , i^0 and k , k^0 , and tending to keep the second of these moving parts in the operative position.

r^1 and r^2 are forks so connected respectively to the movable member d^{10} of the clutch d^1 , d^{10} and the movable portion d^{20} of the clutch d^2 , d^{20} that these parts can be controlled by means of hand levers. 95

s is a hand lever connected by operating rods having elongated eyes s^1 and s^2 , respectively to the fork r^1 and to the fork r^2 , in such a way that the two movable portions d^{10} , d^{20} are active when it is in its mid position. By drawing it into the position denoted by numeral 1 on the drawing, or by 100 pushing it into the position indicated by numeral 2, it is possible to move the second or the first of the said moving parts into inoperative position whilst at the same time leaving the first or the second of such parts 105 in operative position.

t is a pedal connected by suitable rods to a controlling fork u , associated with the movable portion k^0 , of the clutch k , k^0 , and also connected to an operating rod having 110 an elongated eye which connects it to the band of the brake pulley n . In this way by progressively operating this pedal, the movable portion k^0 can first be moved into inoperative position, and then without modifying this last effect, the band of the brake pulley n can be brought into action. 115

v is a pedal connected by a suitable rod to a controlling fork w associated with the movable part i^0 , of the clutch i , i^0 and also connected through a rod having an elongated eye with the band of the brake pulley m . By pressing progressively upon this pedal, the movable portion of the clutch i , i^0 can first be moved into inoperative 120 125 130

position, and then and without modifying this effect, the band of the brake pulley m can be brought into action.

x is another pedal connected by a suitable rod to the band of the brake pulley l , so that this band can be brought into action by depressing the pedal.

By means of pawls, not shown on the drawing, fitted in connection with the lever s , it may be so arranged that when this lever is brought into one of its extreme positions 1 or 2, it may be maintained in the said position as long as may be required.

t^o is a pawl so connected to the pedal t that once this pedal is depressed sufficiently to move the movable piece i^o which it controls into the inoperative position, it is kept in that position. The pawl is moreover so constructed that it may be thrown out of action by means of the foot which operates the said pedal.

The whole arrangement just described enables the following advantageous results amongst others to be obtained:—

25 The feeble motor A^1 is started to operate.

The pedal t is engaged with the pawl. The lever s is brought into the position 1, and with the assistance of any apparatus 30 designed for the purpose, for instance by means of a handle y , the motor is started. With the feeble motor A^1 turning in the common normal turning direction of the two motors, which direction will, for the sake 35 of simplicity, be termed hereafter as the "positive direction", the drive is transmitted through the parts $a^1, e^1, b^1, d^1, d^{1o}, f^1$ to the sun wheel f which is driven in the positive direction. On account of the resistance 40 offered by the shaft c through the intervention of the clutch i, i^o to the rotation of the satellites g as a whole, that is since their axes are fixed, the internally toothed annulus j which carries the brake pulley n 45 is driven in the negative direction.

2. First speed. Cause the feeble motor A^1 to turn alone. Push the pedal t to the bottom. This, by braking the pulley n prevents the rotation of the pulley n in the negative direction just described, and consequently obliges the satellites g to move 50 on the annulus j , overcoming the resistance of the shaft c .

3. Second speed. Let the feeble motor A^1 turn alone. Allow the pedal t to come back to the original position, for this purpose suitably operating upon the pawl mechanism t^o . This operation locks the whole of the differential train and enables 55 a direct grip or drive to be obtained.

4. Third speed. The two motors A^1 and A^2 are caused to turn at the same time. To accomplish this operation, the lever s is put into the mid position so as to start the stronger motor A^2 from the feeble motor

A¹. Then bring the pedal t into the position in engagement with the pawl. In this way operation is effected both of the sun wheel f and of the annulus j in the positive direction, and consequently an operation of the satellites g , and the shaft c , at the same time by the sun wheel and the annulus. The velocity thus obtained is variable at will by modifying, with the assistance of the arrangements provided for that purpose, the drive of one or other of the parts A¹ and A² of the motor.

5. Fourth speed. Leave the two groups A¹ and A² of the motors still turning, but utilize the group A² alone. In order to effect this fourth speed, the operation is as follows:

Bring the lever s into the position 2, thus declutching the group A¹. Then allow the pedal t to move right back, as previously. This obliges the whole differential gear to become again locked and causes the direct operation, but this is effected on this occasion by the second portion alone of the motor.

6. Fifth speed. Leave the two motor groups turning and utilize them at the same time. In order to bring this about, operations of the parts are executed as follows:

Push the pedal t into position to be engaged by the pawl. Then move the lever s into the mid position. This causes direct drive from the two motors.

The braking is obtained by simply operating the pedal x .

8. In order to obtain the reverse drive, operations have to be executed as follows:

Bring all the parts into the respective positions corresponding to the second speed. Then press the pedal v downwards. This brings the movable portion i^o of the clutch i, i^o hitherto operative, into the inoperative position, and then produces a braking action upon the pulley n . The consequence is that the axles of the satellites g are prevented from moving, so that under the action exercised upon them in the positive direction by the sun wheel f , the annulus j is operated, and consequently through the intervention of the clutch k, k^o and the said movable portion i^o then free, the shaft c moves in the negative direction.

It will be understood that, in the case of both motors being utilized, the feeble motor, with its feeble torque, acts on the sun wheel, and the stronger motor with its strong torque acts on the annulus. The sun wheel acts on the satellites at a short distance from the common center of the differential gearing, and the annulus acts on the said satellites at a greater distance from said common center, both acting with the same force in order to drive the planet carrier. The possibility of a perfect balance of unequal torques is thus clearly obvious.

It is to be clearly understood as previously explained that the invention is not limited in any way to the methods of carrying it into effect nor to the particular applications just described.

Various modifications may be made without departing from the principle.

For instance in some cases the two gears b^1 and b^2 may be of the same diameter.

10 In other cases the construction shown in Fig. 2 may be modified by combining with the band of the brake pulley m means suitable for rendering this band operative without at the same time rendering the clutch i , i^0 inoperative. In this way it is possible by utilizing the second portion A^2 of the motor so to operate the satellites g that through the action of the annulus j they roll upon the pinion f , which is held fixed, thus 15 obtaining a supplementary speed.

For constructing the differential change speed mechanism, I may in some cases provide bevel gearing instead of straight cut gear wheels.

25 The improved organization embodying the features of the invention may in some cases comprise motors of the same power, but under these conditions the crankshafts of the motors will be preferably arranged 30 in alinement.

Other means may be provided for controlling the different clutches besides those just described.

Finally, although the invention has been 35 described as applied to powerful automobile vehicles, it is obvious that it may be applied to other apparatus or mechanism.

What I claim and desire to secure by Letters Patent of the United States of America

40 is:

1. In an automobile vehicle, the combination of a driven shaft, two internal combustion engines, one of the engines being of greater power than the other, and both turning in the same direction, a separate crank-shaft operated by each engine, the two crank-shafts each having a pinion keyed thereon, a clutch part for each of said engines mounted to constantly rotate on said 45 driven shaft when its engine is in operation, gear wheels carried by the constantly rotating clutch parts and meshing with said pinions, movable clutch parts associated with said constantly rotating clutch parts, a differential mechanism comprising rotatable concentric spaced annular parts driven respectively through the said clutch connections by said engines, planet pinions in

driven connection with said annular parts, said annular parts having radial leverage 60 with respect to the common axis so arranged that both parts will act with equal force on the planet pinions and will compensate for the unequal torques of the mechanism connecting the annular parts to their respective 65 engines, and clutch means on the driven shaft for selectively connecting said driven shaft to various parts of the differential mechanism whereby variations in the speed of said driven shaft are obtained.

2. In an automobile vehicle, the combination of a driven shaft, two internal combustion engines each having a crank-shaft, one of the engines being of greater horse power than the other, both turning in the same 70 direction and each comprising a number of cylinders and a clutch, the one clutch having developed thereon a stronger torque than the other clutch, a sleeve loosely mounted on said shaft and driven by the clutch of the engine of lower horse-power, a sun wheel carried by said sleeve and planet gearing comprising carrying means having axles with planet pinions fastened thereto, the planet pinions meshing with the sun wheel, a planet sleeve connected to the carrying means and having a brake pulley thereon, a double clutch having an axially immovable loose part at the inner portion thereof also connected to the planet pinion and permitting 75 the carrying means to be clutched to the driven shaft, an annular sleeve mounted loosely on the planet gearing sleeve and having a toothed annulus meshing with the planet pinions, the clutch for cooperation 80 with said annular sleeve and stronger motor for the purpose of driving the said sleeve, a part associated with the said annulus meshing with the planet pinions carrying a band brake and having the exterior 85 part of said double clutch axially and slidably keyed thereto, the double clutch being operative to connect and cause the planet pinion carrying means, the driven axle and the annulus to turn as a whole, braking means on the driven shaft, the planet carrying sleeve and the said annulus, and clutch operating means on the axially slidable parts of the clutch between the feebler motor and the sun wheel and between the 90 stronger motor and the annulus and also operating with the remaining parts to effect different steps of forward torque and one step of rearward torque on the driven shaft.

In witness whereof I affix my signature.
EMILE DESMOULINS.
